UNITED STATES PATENT OFFICE.

FLOYD L. CHAMBERLAIN, OF WATERLOO, IOWA.

CLOTHES WRINGER.

Original application filed February 17, 1921, Serial No. 445,702. Divided and this application filed April 17, 1922. Serial No. 554,151.

To all whom it may concern:

Be it known that I, FLOYD L. CHAMBERLAIN, a citizen of the United States of America, and a resident of Waterloo, Black-hawk County, Iowa, have invented certain new and useful Improvements in Clothes Wringers, of which the following is a specification.

My invention relates to improvements in clothes wringers, and the object of my improvement is to supply in a wringer effective and easily operated means for delivering clothing which has passed through the rolls to either of opposite sides.

5 This object I have accomplished by the means which are hereinafter described and claimed, and which is illustrated in the accompanying drawings, in which Fig. 1 is a side elevation of my improved wringer with 20 parts sectioned away; Figs. 2 and 3 are elevations of opposite ends thereof with parts removed or sectioned; Fig. 4 is a top plan thereof, and Fig. 5 is an under plan thereof with parts broken away.

25 Similar numerals of reference denote corresponding parts throughout the several views.

The rigid U-shaped frame of the wringer is composed of outwardly channeled vertical 30 bodies 3 connected at their lower ends by a horizontal tubular member 2 and having at the top a swinging closure and compression-member 16 pivoted at 17 to the top of one of the bodies 3 with its other end releasably 35 interlocked at 18 with an orificed casing-body 1 which is mounted over the channel of the other body 3. The usual superposed coacting rolls 9 and 10 are mounted in suitable relatively vertical adjustable bearings 40 removably placed in seat openings in said bodies 3 and connected by intermeshing gearing. The lower parts of the bodies 3 are orificed in horizontal alinement to serve as bearing openings for opposite end parts 45 of the rock-shaft 4, one end of which is bent angularly to provide a crank or arm 6 positioned within the hollow of said casing-member 1. Adjacent the inner faces of the bodies 3 like shaped and positioned cranks 50 are rigidly mounted on the rock-shaft 4. The numeral 8 denotes a substantially rectangular chute whose ends are rimmed, and each rim shaped with a downwardly directed medial part orificed to receive a 55 crank-pin or pintle on the end of the ad-

jacent crank 5 whereby the chute is mounted below said rolls to be rocked and swung thereunder to opposite sides of the wringer at opposite inclinations in order to be positioned at either side to receive and deliver 60 clothes passing from the rolls on that side. This swinging of the chute may be easily manually effected, and the chute may be releasably locked in either of its said oppositely inclined positions. Alined openings 65 14 are provided in opposite flanges of the frame-member 3 between which is positioned the crank 6. These openings are preferably notches in the edges of the flanges to permit insertion of narrowed parts of a trans- 70 verse rocking and locking member having depending end finger-pieces 15 outside said flanges and having a depending rectangular locking part 13 between the flanges. Before the chute 8 is shifted, said locking member 75 is swung upwardly to release the crank 6 with whose beveled end the lower edge of the part 13 is normally engaged, and after the chute is rockingly shifted to its opposite position thus tilting the crank 6 oppositely, 80 the locking member is then released to swing down and engage its part 13 against the end of the crank.

The angle-bar ribs 7 are secured on the under side of the chute 8 transversely near 85 its end so that their flanges may ride slidingly across the shaft 4, as shown in Fig. 2.

Having described my invention, what I claim as new, and desire to secure by Letters Patent, is:

1. A clothes wringer, comprising in combination, a frame, a pair of coacting rolls rotatably mounted therein, a rock-shaft provided with cranks and mounted in said frame with one end bent angularly, a deflector positioned below said rolls and above said rock-shaft, pivotally mounted on said cranks, and a releasable gravity-locking device adapted to interlock with the bent end of said rock-shaft when said deflector is in 100 either of oppositely extended positions.

2. A clothes wringer, comprising in combination, a frame, a pair of coacting rolls rotatably mounted therein, a rock-shaft provided with cranks and mounted in said 105 frame, a deflector pivotally mounted on said cranks to be extended to either side of said rolls, said rock-shaft having a terminal crank-arm, and a rock-body mounted on said frame having a depending rib for releasable 110

locking engagement with said crank-arm held by gravity when the crank-arm is in either of oppositely-inclined positions.

3. A clothes wringer, comprising in combination, a frame, a pair of coacting rolls mounted in said frame for reverse rotations, a rock-shaft provided with cranks and mounted in said frame under said rolls, said rock-shaft having a terminal crank-arm, a rock-body mounted on said frame to rock transversely in the path of movement of said

crank-arm and having a part projecting toward said arm to releasably interlock therewith, said rock-body having terminal handles without the frame, and said deflector having transverse ribs adapted to ride across said rock-shaft slidingly when the shaft is rocked. ¹⁵

Signed at Waterloo, Iowa, this 17th day of March, 1922.

FLOYD L. CHAMBERLAIN.
